UNITED STATES PATENT OFFICE.

WILLIAM L. LANGE, OF NEW YORK, N. Y.

TUBE RESONATOR FOR BANJOS.

Application filed October 28, 1921. Serial No. 511,005.

To all whom it may concern:

Be it known that I, WILLIAM L. LANGE, a citizen of the United States, residing in New York city, in the county of New York 5 and State of New York, have invented certain new and useful Improvements in Tube Resonators for Banjos, of which the following is a specification.

This invention relates to musical instruments and particularly to banjos, and one object of the invention is to provide a banjo in which the tone ring of the banjo is supported by means having minimum contact with the tone ring, this means also conducting to a powerful and singing tone of unusual volume and carrying power.

Another object is to provide a banjo in which the tone ring is supported by spaced or bridging supporting means having minimum muting contact with the tone ring whereby the tone ring has a maximum of vibrant quality.

Another object is to provide a banjo in which the tone ring is supported by a series 25 of tubes spaced apart having minimum muting contact with the tone ring, the tubes at their supporting ends communicating with the interior of the head portion or tone chamber of the banjo, and communicating at 30 their opposite ends with the atmosphere and conducting to a powerful and singing tone of unusual volume and carrying power.

Another object is to provide a banjo in which the rim, tone ring, diaphragm and 35 straining ring or band are all supported by means having minimum muting contact with the tone ring.

Another object is to provide a banjo having inner enclosure means extending from 40 the upper or top edge of the frame or shell to a line slightly above the lower edge of the tone ring and in proximity to the under side of the vibratory diaphragm, the enclosure means providing relatively narrow space between the diaphragm and tone ring and said means, which narrow space communicates 45 with space between the lower edge of the rim of the banjo and the upper edge of the frame, for passage of vibrations from the interior 50 of the banjo through said narrow space and out through said space between the rim and frame, the intention being that all tones and vibrations shall as far as possible, pass through said narrow space and the space between the rim and frame and through the 55 before mentioned supporting tubes, thus

avoiding the direct passage of the vibrations from the interior or tone chamber of the banjo sidewise and the striking of the body of the performer by these vibrations and the cutting short of the vibrations.

A principal feature of my present construction lies in the bridging effect this construction permits due to the tubular support of the tone ring at intervals. This space- 65 supporting, or bridging-support, of the tone ring gives a minimum of muting contact to the tone ring thereby permitting the said ring to have a maximum of vibrant quality. Heretofore, the tone ring as ordinarily supported is in full contact with the supporting means thereby smothering the vibrant qualities of the tone ring due to the loss of resiliency owing to the ring having a full bed support and contact. The bridging of the 70 tone ring between its supports, and preferably these supports being tubular is a step in advance of all other constructions and the tone quality of the banjo is thereby increased.

In the accompanying drawing, which shows by way of example one embodiment of the invention and forms part of this specification, Figure 1, is a plan view of the head of the banjo and a portion of the neck.

Figure 2, is a fragmentary elevation of the head of the banjo, on the line 2-2 of Fig. 1, showing a portion of the interior of the frame and of the interior of the enclosure member or inner frame band, and showing 90 in front view the straining member or rods, the brackets therefor, and the supporting tubes.

Figure 3, is a fragmentary elevation on an enlarged scale, of the head of the banjo substantially similar to Fig. 2, but omitting the front view of the straining members, brackets and tubes.

Figure 4, is a bottom plan view of the head of the banjo, and showing the under side of the neck connected to the head by the cross-bar.

Similar reference characters denote similar parts throughout the several views.

To the accomplishment of the above objects and such other objects as will be disclosed in the course of the following description for illustrating the invention by one embodiment thereof, the invention being defined by the appended claims, the invention comprises the annular frame or shell 10, 105 preferably of wood, provided with a series

of apertures 11 extending therethrough from its lower to its upper edge, and spaced around the circumference of the frame.

The diameter of the apertures 11 for the greater part of their length, is the diameter of the exterior of the tubes later described, the diameter of these apertures being enlarged near their lower ends, as at 12, for the purpose later mentioned.

10 Each tube of the series of metal tubes, such as 13, Figs. 2 and 3, is received in the upper end of an aperture 11, the tube being secured at its lower end in the aperture as by the screw bolt 14 passing through the frame 10 from the interior thereof outwardly, through the tube 13 and engaging in the bracket 15, whereby the tube 13 is supported and the bracket 15 is held securely to the exterior of the frame 10.

15 The brackets 15 are of metal and are substantially triangular in shape when viewed from the side, and are provided near their outer edges with threaded apertures 16, which may be inwardly inclined.

20 The rim 17 is an annular band, preferably metal, having an annular groove 18 in its top edge and a bearing face 19 on its bottom edge.

25 The tone ring 20 is received closely within the rim 17 but permits passage of the vibratory diaphragm or vellum 21 between the interior side of the rim and the exterior of the ring 20, the diaphragm or vellum contacting with the tone ring and being supported thereby, the edge of the diaphragm being turned or folded over a squared strain-

30 ing or flesh hoop 22, in such manner that when the rim 17 is drawn tightly downward so that the face 19 is in contact with the diaphragm or vellum this will be held at its edge and stretched, and the hoop 22 will be supported by the diaphragm or vellum.

35 The tone ring 20 is supported on the upper ends of the series of tubes 13, by resting on a substantially segmental portion of the wall of each tube, the remainder of the bore of the tube, being open and communicating with the interior of the banjo for the passage of vibrations therethrough.

40 It will be noted that the tone ring 20, is thus supported by means spaced apart, having minimum muting contact with the tone ring, the tone ring bridging the space between the supports and having a maximum of vibrant quality.

45 It will also be noted that the tone-ring 20, diaphragm or vellum 21, flesh hoop 22, and rim 17 are all supported by the series of tubes 13, which in turn are supported by the screw-bolts 14.

50 Straining members or rods 23 are provided for the brackets 15, these members having stems 24 the lower ends of which pass through the brackets and are threaded for

engagement with the interiorly threaded handles 25 which engage the under sides of the brackets.

55 It will be noted that the tubes, tone-ring, vibratory diaphragm, straining band, rim, brackets and straining members are all primarily supported by a single means, that is, the screw bolts 14 appurtenant to the frame or shell; and that by removal of the screw bolts 14 all the parts of the banjo 60 head, except the inner enclosure member later described, may be disassembled.

65 The inner enclosure member or inner frame band 27 is an annular band of relatively light metal, retained in operative position by being sprung at its lower end into an interior annular rabbet 28 in the top edge of the frame or shell 10. The band 27 extends upwardly to a line slightly above the upper ends of the tubes 13 and slightly above the lower edge of the tone ring 20, the band 27 being spaced away from the tone ring, there being a narrow space 29 between the under side of the diaphragm or vellum 21 and the top edge of the band 27 70 communicating with the space 30 comprised between the under side of the tone ring 20 and the top edge of the shell or frame 10, which space 30 communicates with the space 31 between the lower edge of the flesh hoop 22, or broadly speaking the lower edge of the rim 17, and the top edge of the shell or frame, and opening to the atmosphere for passage of vibrations, the space 29 also permitting passage of vibrations through the tubes 13.

75 The annular space between the frame 10 and tone ring 20 and between the rim 17 and the band 27 constitutes an outwardly opening chamber receiving vibrations from said frame, ring, rim and band and from said space 29.

80 The apertures 11 are enlarged near their lower ends, as at 12, for receiving the grommets or terminals 32, the space 33 afforded at the lower ends of the tubes 13 and by the adjoining interiors of the grommets 32 providing a somewhat bell-mouthed chamber conduced to the amplification of the vibrations emitted from the tubes 13.

85 Having thus described my invention, it should be understood that there may be modifications thereof and variations therein without departing from the spirit of the invention or exceeding the scope of the appended claims.

90 What I claim and desire to protect by Letters Patent is:

95 1. In a banjo, a frame having a series of spaced apertures therethrough around the frame extending in the line of depth of the frame and communicating at one of their ends with the atmosphere, tubular members having portions supported in said apertures 100 at the ends thereof opposite to the first men-

- tioned ends and having portions extending beyond the frame towards the front of the banjo, a vibratory annular member supported on the ends of said extending portions and permitting passage of sound from the interior of the banjo into the tubular members and thence by way of said apertures to the atmosphere, and means for retaining said annular member on the ends of the extending portions of the tubular members.
2. In a banjo, a frame having a series of spaced apertures therethrough around the frame extending in the line of depth of the frame and communicating at one of their ends with the atmosphere, tubular members having portions supported in said apertures at the ends thereof opposite to the first mentioned ends and having portions extending beyond the frame towards the front of the banjo, a vibratory annular member supported on the ends of said extending portions and permitting passage of sound from the interior of the banjo into the tubular members and thence by way of said apertures to the atmosphere, a vellum extending over said annular member, and means for stretching the vellum over said annular member and thereby retaining the annular member on the ends of said extending portions of the tubular members.
3. In a banjo, a frame having a series of spaced apertures therethrough around the frame extending in the line of depth of the frame and communicating at one of their ends with the atmosphere, tubular members having portions supported in said apertures at the ends thereof opposite to the first mentioned ends and having portions extending beyond the frame towards the front of the banjo, a tone ring supported on the ends of said extending portions and permitting passage of sound from the interior of the banjo into the tubular members and thence by way of said apertures to the atmosphere, a vellum extending over said tone ring, means for stretching the vellum over said tone ring and thereby retaining the tone ring on the ends of said extending portions of the tubular members, and a frame band secured to said frame adjacent to the extending portions of the tubular members in the interior circumferential space formed by the extending portions of the tubular members and extending to a line somewhat above the free edge of the tone ring and spaced away from the extending portions of the tubular members and the tone ring.
4. In a banjo, a frame having a series of spaced apertures therethrough around the frame extending in the line of depth of the frame and communicating at one of their ends with the atmosphere, tubular members having portions supported in said apertures at the ends thereof opposite to the first men-
- tioned ends and having portions extending beyond the frame towards the front of the banjo, a tone ring supported on the ends of each of the extending portions and permitting passage of sound from the interior of the banjo into the tubular members and thence by way of said apertures to the atmosphere, means in said apertures at the ends thereof communicating with the atmosphere having bores of the same diameter as the bores of the tubular members for providing coincidence of the bores of said members and said means for unbroken passage of sound to the atmosphere through said members and said means, and means for retaining the tone ring on the ends of the extending portions of the tubular members.
5. In a banjo, a frame having a series of spaced apertures therethrough around the frame extending in the line of depth of the frame and communicating at one of their ends with the atmosphere, and tubular members having portions received in said apertures at the ends thereof opposite to the first mentioned ends and having portions extending beyond the frame towards the front of the banjo for passage of sound from the interior of the banjo through the tubular members by way of said apertures to the atmosphere.
6. In a banjo, a tone ring, an annular frame having a series of spaced apertures therethrough around the frame extending on the line of depth of the frame and communicating at one of their ends with the atmosphere at the back of the banjo, and means cooperating between the tone ring and said frame at the ends of said apertures opposite to the first mentioned ends for supporting the tone ring on the frame and permitting passage of sound from the interior of the banjo through said means and the apertures of the frame to the atmosphere at the back of the banjo.
7. In combination, a wooden frame having spaced vertical bores therethrough; metal tubes open at both ends and received in said bores and projecting well above the upper edge of the frame; brackets on the outside of the frame; bolts through the frame, tubes and brackets and forming means for holding these parts in place and permitting passage of sound through the tubes; a metal tone ring resting on the tops of said tubes near the outer edge of the tops to leave the tubes partly open at their tops; a vellum disposed over said ring and having a flesh hoop; a metal tension rim disposed around said vellum, ring and tubes and resting on said hoop; and means engaging over said tension rim and passing through said brackets for exerting strain upon the vellum.
8. In combination, a deep wooden frame having widely spaced vertical bores therein;

- metal tubes open at both ends and of less internal diameter than and fast in said bores terminating about half-way of the bores and projecting well above the upper 5 edge of the frame; grommets inset in and slightly projecting from the lower ends of said bores and cooperating with the tubes for providing coincidence of the bores of the tubes with the bores of the frame; 10 brackets on the outside of the frame; bolts passing through the frame, tubes and brackets and forming means for holding these parts in place and permitting passage of sound through the tubes; a metal tone 15 ring resting on the top of said tubes near the outer edge of the tops to leave the tubes open for passage of sound; a vellum disposed over said tone ring and having a flesh hoop; a metal tension rim disposed 20 around said vellum, ring and tubes and resting on said hoop; and means engaging over said tension rim and passing through said brackets and provided with nuts for exerting strain on the vellum.
- 25 9. In combination, a frame; a series of open tubes mounted on the frame; a tone ring on said tubes; a vellum tensioned over said ring; and a thin metal inner band mounted on said frame within the interior 30 circumferential space formed by the series of tubes and having its upper edge terminating near the upper ends of the tubes.
10. In combination, a frame; a tone ring spaced above the frame; a vellum tensioned 35 over said ring; and a thin inner band mounted on said frame extending nearly but not quite to the top level of the ring and exposed between the frame and tone ring.
- 40 11. In combination, a wooden frame; a tone ring spaced above the frame; a vellum tensioned over said ring; and an outwardly exposed metal inner band set in and projecting above said frame and free of contact 45 with the vellum or tone ring.
12. In combination, a frame; a tone ring spaced above the frame; a vellum tensioned over said ring; an inner band mounted on said frame and having its entire upper edge 50 free; and means cooperating with the band to form an outwardly open outer chamber therearound.
13. In combination, a frame; tubes mounted on the frame; a ring on said tubes; 55 a vellum tensioned over said ring; a tensioned rim secured around said ring and tubes; and an inner band mounted on said frame and extending above the lower level of said rim cooperating with said rim to 60 form an outer chamber.
14. In combination, a frame; a tone ring spaced above the frame; a vellum tensioned over said ring; a tension rim secured around and spaced from said ring; and an inner 65 band mounted on said frame and cooper-

ating with the tension rim and vellum to form an outer chamber.

15. In combination, a frame; tubes mounted on the frame; a tone ring on said tubes; a vellum tensioned over said ring; a rim secured around said series; and an inner band mounted on said frame and cooperating with the tension rim and ring to form an outer chamber.

16. In combination, a frame; a series of tubes mounted on the frame; a tone ring above said tubes; a vellum tensioned over said ring; and means cooperating to form inner and outer chambers into the latter of 75 which the tubes open.

17. In combination, a frame having bores therein; tubes in said bores projecting well above the frame; brackets on the outside of the frame; bolts for holding these parts in place; a tone ring on the top of said tubes; a vellum disposed over said tone ring; a rim secured to said vellum and around said ring and tubes; strain hooks between said rim and brackets; and a thin inner band mounted in said frame and extending to 80 near said vellum within the tone ring and cooperating with the ring, rim, vellum and frame to form outer and inner chambers.

18. In combination, a frame; a series of tubes supported by the frame; a tone ring supported by the tubes and spaced above the frame leaving a sound passage therebetween; a vellum tensioned over said ring; and a band mounted on said frame and having its upper edge disposed within the ring close to the vellum and cooperating with the vellum to form a narrow passage varied in width by the vibration of the vellum.

19. In combination, a frame; a series of tubes supported by the frame; a tone ring supported by the tubes and spaced above the frame leaving a sound passage therebetween; a vellum tensioned over said ring; and a thin metal inner band mounted on 105 said frame and having a thin upper edge disposed close to the vellum to form a narrow passage.

20. In combination, a frame; a series of tubes mounted on the frame; a tone ring on said series; a vellum tensioned over said ring; a tension rim secured around said ring and series; and a thin inner band mounted on said frame and having its upper edge disposed close to the vellum and co-operating with the vellum to form a narrow passage varied in width by the vibration of the vellum; said inner band cooperating with the tone ring and vellum and the tension rim, to form an outer resonating chamber into which said narrow passage and said tubes open.

21. In combination, a frame having bores therein; a series of tubes in said bores and projecting above the frame; a tone ring above the frame and supported by said 130

- tubes; a vellum tensioned over said ring; a tension rim secured around said ring and series; and a thin inner band mounted on said frame to form therewith a main inner 5 resonance chamber and having its upper edge disposed close to the vellum and cooperating with the vellum to form a narrow passage varied in width by the vibration of the vellum.
- 10 22. In combination, a frame; a series of tubes mounted on the frame; a tone ring on said tubes; a vellum tensioned over said ring; a tension rim secured around said ring and series; and a thin inner band mounted 15 on said frame and co-operating with the frame to form a main inner resonance chamber; and having its upper edge disposed close to the vellum and cooperating with the vellum to form a narrow passage; said inner band cooperating with the tone ring and vellum, and the tension rim, to form an outer 20 resonating chamber communicating with the inner chamber.
23. In combination, a frame having bores therein and a rabbet at the upper inner edge; a series of tubes in said bores projecting well above the frame; brackets on the outside of the frame; bolts for holding these parts in place; a tone ring on the top of said tubes; a vellum disposed over said tone ring and provided with a tension rim around said series; and a thin metal inner band sprung at its lower edge into said rabbet and extending to near said vellum a slight distance from and within the tone ring and 25 cooperating with the frame to form an inner chamber, and cooperating with the vellum to form a narrow slit opening; and cooperating with said rim to form an outer 30 resonance chamber receiving vibrations from the inner chamber, from within said tubes and from the surface of said tubes, said vellum, said tone ring, said thin band, and said rim. 35 40

WILLIAM L. LANGE.
